Primary Examiner — Janice Hallmark

(57) CLAIM

The ornamental design for an eagle cellular phone holder, as shown.

DESCRIPTION

FIG. 1 is a front perspective view of an eagle cellular phone holder showing our new design;

FIG. 2 is a front elevational view thereof;

FIG. 3 is a side elevational view thereof.

FIG. 4 is a back elevational view thereof; and,

FIG. 5 is a front perspective view of the eagle cellular phone holder of FIG. 1 shown in an alternate position of use with a cellular phone being held therein.
